UNITED STATES PATENT OFFICE.

GARRY I. MIX, OF YALESVILLE, CONNECTICUT.

DESIGN FOR A HANDLE OF A SPOON.

SPECIFICATION forming part of Design No. 14,349, dated October 16, 1883.

Application filed August 24, 1883. Term of patent 7 years.

To all whom it may concern:

Be it known that I, GARRY I. MIX, of Yalesville, in the county of New Haven, and in the State of Connecticut, have invented certain 5 new Improvements in Designs for the Handles of Spoons, Forks, Ladles, &c.; and I do hereby declare that the following is a full, clear, and exact description thereof, reference being had to the accompanying drawings, making a 10 part of this specification, in which—

Figure 1 represents a face view of a spoon, and Fig. 2 is a like view of the back of the same.

Letters of like name and kind refer to like 15 parts in each of the figures.

This invention relates to a design for the handles of spoons, forks, ladles, and other like articles of table-service; and it consists in the configuration and ornamentation, as herein- 20 after described, and as shown in the accompanying illustration.

At points between the ends of the upper enlarged portion of the face of the handle are three parallel ornamental bands, a , which extend 25 transversely across the same, and are each composed of a side line or side lines enclosing a space upon or within which are a number of squares arranged with their longest axes in a line. Between the end of the handle 30 and the lower band a are three panels, within

the upper and lower of which panels, a' and a'' , respectively, are flowers, while the center panel, a'' , is plain, unless a row of beading, a'' , is extended across its upper end. The ornamented portion of the handle is preferably 35 inclosed by a bead, a'' , which extends around the same, at or just within the edge, and just below the lower band a is a dash, a'' , that terminates at its lower end in a point; but either of said features may be omitted, if desired. The back of the handle is similar to the front, except that the center band a is omitted, and the flowers within the upper panel, a' , and immediately above the lower band are preferably smaller than are those 45 upon said face.

Having thus fully set forth the nature of my invention, what I claim as new is—

The design for the handles of spoons, forks, ladles, &c., consisting of the transverse bands 50 a , ornamented panels a' and a'' , and plain panel a'' , substantially as shown and described.

In testimony that I claim the foregoing I have hereunto set my hand this 10th day of August, A. D. 1883.

GARRY I. MIX.
